UNITED STATES PATENT OFFICE.

ERNEST LOUIS RANKIN, OF LONDON, ENGLAND, ASSIGNOR OF ONE-HALF TO CHARLES WILLIAM WHITMORE HANBIDGE, OF LONDON, ENGLAND.

GRAMOPHONE.

Application filed February 25, 1925, Serial No. 11,565, and in Great Britain March 1, 1924.

This invention relates to improvements in the winding mechanism of motors for use in gramophones and a governor or speed controlling means therefor.

5 According to this invention a circular plate is arranged underneath and concentric with the record carrying table and may be adapted to rotate or remain stationary. Pads of felt or the like are arranged on 10 arms pivotally supported by the underside of the record table, the pivoted arms having suitably arranged weights attached thereto, which weights, upon rotation of the record table, are caused by centrifugal action to 15 swing outwardly, thus causing the arms to rock and the pads to contact with the plate, thereby obtaining a braking action between the circular plate and record carrying table acting as a governor or speed control device.

20 In the accompanying drawings which illustrate two forms of the invention,

Figure 1 is a plan view of a machine embodying the invention, a portion of the record table, governing plate and casing being 25 broken away.

Figure 2 is a sectional view on the line 2—2 of Figure 1.

Figure 3 is a plan view of a modified form of the invention.

30 Figure 4 is a section on the line 4—4 of Figure 3.

In the machine shown in Figures 1 and 2 the record carrying table 1 has arranged beneath it and concentric therewith a circular plate 2 adapted to act as a governor plate. Upon the underside of the record table 1, near the periphery thereof are pivotally mounted several weighted arms 3 carrying leaves 4 upon which are mounted pads of 35 felt or the like. Upon rotation of the record table the weighted arms 3 are caused by centrifugal action to swing outwardly, thus causing the pads carried by the leaves 4 to contact with the upper face of the governor 40 plate 2 (as shown in chain lines Figure 2), thereby obtaining a braking action. Thus this device acts as a governor, whilst the weight of the record table in the first instance prevents the spring motor of the 45 gramophone from racing. The distance between the record table 1 and governor plate 2 can be adjusted as desired in a manner to be hereinafter described in order to retard or accelerate the braking action of the 50 leaves 4.

The plate 2 is carried on a sleeve 5 surrounding the casing 6 of the spindle 7 which drives the record table 1, the sleeve 5 being 55 slidable within limits longitudinally upon the spindle casing 6. Surrounding the sleeve 5 is a sleeve 8 which is slotted to allow an auxiliary sleeve 9, which is mounted on the lower end of the sleeve 8, to be connected by screws or the like to the sleeve 5 and thus be movable therewith. A peripheral groove 10 in the auxiliary sleeve 9 is adapted to receive pins mounted in the forked end of a lever 11 pivoted at 12 and actuated by a spring 13 which tends to retain the sleeves 5 and 9 in a lowered position. A rod connects the other 60 end of the lever 11 with one end of another lever 14 which is pivoted at 15 on the underside of the top of the machine casing and actuated and adjusted by a governor control screw 16 extending through said top and engaging the other end of the lever 14. When the screw 16 is turned to raise the arm of the lever 14 which is connected to the governor screw the motion is transmitted to the arm 11 which raises the sleeves 5 and 9 65 and consequently moves the plate 2 nearer to the record table 1.

Winding of the motor 17 may be effected by the rotation of radial arms 18, rotatable concentrically with the plate 2 and record 70 table 1 and fixedly mounted upon a plate 19 attached to or integral with the sleeve 8. The motor may be fully wound by a few rotations of these arms which are arranged above the top of the gramophone casing and, owing to their position, are not cumbersome, although they are always attached to the machine. A toothed winding wheel 20 fixedly mounted on the sleeve 8 meshes with another toothed wheel 21 integral with the 75 casing of the spring motor 17.

A ratchet wheel 22 concentric with and fixed upon a toothed wheel 23 is engaged by pawls 24 carried by the underside of the spring motor casing. The toothed wheel 23 80 meshes with a toothed wheel 25 keyed upon a stub shaft 26 which also carries a toothed wheel 27 which is in mesh with another toothed wheel 28 keyed upon the spindle 7. Thus upon the rotation of the radial arms 85 the spring is wound up, the pawls 24, by their engagement with the ratchet wheel 22, preventing rotation of the record table during this operation.

In this form of winding, the motor when 90

unwinding causes rotation of the sleeves 5 and 8 around the spindle casing in the opposite direction to the rotation of the record table. Consequently the radial winding arms 18 which are attached to the sleeve 8, and the plate 2 which is mounted on the sleeve 5, are rotated in the same direction as the sleeves.

In the modified construction shown in Figures 3 and 4 two sleeves 30 and 37 are mounted on the spindle casing 6, the sleeve 30 being non-rotatable relatively to the spindle casing.

A peripheral groove 31 in a non-rotatable sleeve 32 carrying the plate 2 receives pins carried in the forked end of a lever 33 pivoted at 34 on the upper side of the top of the machine casing and actuated by a governor screw 35 against the action of a spring 36 which is arranged between the other arm of said lever and the top of the machine casing. Actuation of the lever 33 causes the sleeve 32 to slide upon the sleeve 30, and the plate 2 carried upon the said sleeve 32 can thus be moved towards or away from the record table 1. The sleeve 37, on which the toothed wheel 38 is keyed, extends to a base plate 39 and is rotatable relatively to the spindle casing. A ratchet wheel 40 mounted concentrically on the sleeve 37 and a pawl 41 mounted upon the base plate 39 allow rotation of the toothed wheel 38 and sleeve 37 only during winding up of the motor, which is effected by the aid of a bevel drive, one bevel wheel 42 of which is integral with the rotatable sleeve around the spindle casing. The other bevel wheel 43 is mounted upon the shaft of a winding handle 44. The plate 2 is adapted to be keyed to the sleeve 32 and is therefore not rotatable.

The toothed wheel 38 meshes with another wheel 45 keyed on the spindle of the spring motor 17 and thus rotation of the wheels 38 and 45 by the bevel drive winds up the spring. Integral with or fixed upon the motor casing, which is rotated as the spring unwinds, is a toothed wheel 46 which engages a wheel 25 keyed to a stub shaft 26 carrying another toothed wheel 27 which meshes with a wheel 28 mounted upon the spindle 7.

In order to facilitate easy running of the mechanism the toothed wheels may be mounted upon ball or roller bearings whilst a similar arrangement may be provided between the spindle and spindle casing.

A pin projects inwardly of the sleeve 32 and is adapted to engage a slot or keyway in the sleeve 30 attached to the spindle casing.

Owing to the arrangement of gearing between the motor and the record table or central spindle, it is necessary to have only a short wind motor which therefore requires

less winding and less effort and allows greater steadiness of the entire machine during rewinding.

I claim:

1. A gramophone comprising a frame, a plate carried by the frame, a tubular casing mounted on said plate, a spindle supported in said casing, means for rotating the spindle, a record carrying table mounted upon the spindle, a sleeve slidably mounted upon said tubular casing, a governor plate mounted upon said sleeve and arranged beneath the record carrying table, arms pivotally mounted upon the record table, and leaves carried by said arms and movable into contact with the governor plate to retard the speed of the record carrying table.

2. A gramophone comprising a frame, a plate carried by the frame, a tubular casing mounted on said plate, a spindle supported in said casing, means for rotating the spindle, a record carrying table mounted upon the spindle, a sleeve slidably mounted upon said tubular casing, a governor plate mounted upon said sleeve and arranged beneath the record carrying table, arms pivotally mounted upon the record carrying table, leaves carried by said arms and movable into contact with the governor plate by centrifugal action upon the arms, and means for adjusting the distance between the said governor plate and the record carrying table.

3. A gramophone comprising a frame, a plate carried by said frame, a tubular casing mounted on said plate and having interior and exterior bearing surfaces, a spindle supported in said casing, means for rotating the spindle, a record carrying table mounted upon the spindle, a peripherally grooved sleeve slidable upon the casing, a governor plate carried upon the sleeve and arranged beneath the record carrying table, a pivotally mounted arm having one end extending into the groove of the slidable sleeve, arms pivotally mounted on the record carrying table, and leaves carried by said arms and movable into contact with the governor plate.

4. In a gramophone, a tubular casing having interior and exterior bearing surfaces, a spindle supported in said casing, a record carrying table mounted on said spindle, means for rotating the spindle, a sleeve arranged around the casing and movable longitudinally thereon, means for adjusting the position of said sleeve, a governor plate on said sleeve, arms pivotally mounted upon the record table, and leaves associated with said arms, the said leaves moving into contact with the governor plate to retard the speed of the record carrying table.

5. A gramophone comprising a tubular casing having interior and exterior bearing

surfaces, a spindle supported in said casing, a record carrying table mounted on said spindle, means for rotating the spindle, a sleeve arranged around the casing and movable longitudinally thereon, a governor plate mounted on said sleeve and arranged beneath the record carrying table, means for normally retaining the governor plate at its maximum distance from the record carrying table, means for moving the sleeve to adjust the distance between the said governor plate and the record carrying table, arms pivotally mounted upon the record table, and leaves associated with said arms, said arms being caused by centrifugal action to move said leaves into contact with the governor plate to retard the speed of the record carrying table.

6. A gramophone comprising a tubular casing having interior and exterior bearing surfaces, a spindle supported in said casing, a record carrying table mounted on said spindle, means for rotating the spindle, a sleeve arranged around the casing, means for rotating the sleeve, a governor plate on said sleeve, arms pivotally mounted upon the record carrying table and leaves associated with said arms, the leaves moving into contact with the governor plate to retard the speed of the record carrying table.

7. A gramophone comprising a tubular casing having interior and exterior bearing surfaces, a spindle supported in said casing, a record carrying table mounted on said spindle, means for rotating the spindle, a sleeve arranged around the casing, means for rotating the sleeve, means for adjusting the position of said sleeve on the tubular casing, a governor plate on said sleeve, arms pivotally mounted upon the record carrying table, and leaves associated with said arms,

the leaves moving into contact with the governor plate to retard the speed of the record carrying table.

8. A gramophone comprising a tubular casing having interior and exterior bearing surfaces, a spindle supported in said casing, a record carrying table mounted on said spindle, means for rotating the spindle, a peripherally grooved sleeve arranged around the casing, means for rotating the sleeve, a pivotally mounted arm for moving said sleeve having one end extending into the groove of the slidable sleeve, means for moving the arm to any desired position, a governor plate on said sleeve, arms pivotally mounted upon the record carrying table and leaves associated with said arms, the leaves moving into contact with the governor plate to retard the speed of the record carrying table.

9. A gramophone comprising a tubular casing having interior and exterior bearing surfaces, a spindle supported in said casing, a record carrying table mounted on said spindle, means for rotating the spindle, a peripherally grooved sleeve arranged around the casing, a governor plate on said sleeve, means for rotating the sleeve, a pivotally mounted arm for moving said sleeve having one end extending into the groove of the slidable sleeve, means for moving the arm to any desired position, means for normally moving the governor plate to its maximum position from the record carrying table, arms pivotally mounted upon the record carrying table, and leaves associated with said arms, the leaves moving into contact with the governor plate to retard the speed of the record carrying table.

ERNEST LOUIS RANKIN.
